UNITED STATES PATENT OFFICE.

ALFRED A. GLIDDEN AND JOSEPH E. PERRAULT, OF WATERTOWN, MASSACHUSETTS,
ASSIGNORS TO HOOD RUBBER COMPANY, OF WATERTOWN, MASSACHUSETTS, A
CORPORATION OF MASSACHUSETTS.

DESIGN FOR A BATTERY BOX.

Application filed January 24, 1924. Serial No. 8,383. Term of patent 14 years.

To all whom it may concern:

Be it known that we, ALFRED A. GLIDDEN and JOSEPH E. PERRAULT, citizens of the United States, residing at Watertown, in the county of Middlesex and Commonwealth of Massachusetts, have invented a new and original Design for a Battery Box, of which the following is a specification, reference being had to the accompanying drawing, forming part thereof.

In this drawing, the figure is a perspective view of a battery box showing our new design.

We claim:

The ornamental design for a battery box as shown.

ALFRED A. GLIDDEN.
JOSEPH E. PERRAULT.
